HEATER

William A. Marshall and Dubart A. Moore, Dallas, Tex.,
assignors to Dearborn Stove Company, Dallas, Tex.,
a corporation of Texas

Filed July 28, 1959, Ser. No. 56,968

Term of patent 14 years

(Cl. D81—10)

Fig. 1

Figure 1 is a perspective view of the front of a heater showing our new design;

The side of the heater opposite that shown in Figures 1 and 2 is plain and substantially identical to that of the side shown in Figures 1 and 2.

We claim:

The ornamental design for a heater, substantially as shown and described.
